US0D1058003S

(12) **United States Design Patent** (10) **Patent No.:** **US D1,058,003 S**
(45) **Date of Patent:** **** Jan. 14, 2025**

(54) **LED PACKAGE**

(71) Applicant: **KAISTAR Lighting (Xiamen) Co., Ltd.**, Xiamen (CN)

(72) Inventors: **Jingqiong Zhang**, Xiamen (CN); **Yiqun Li**, Xiamen (CN)

(73) Assignee: **Bridgelux Optoelectronics (Xiamen) Co., Ltd.**, Xiamen (CN)

(**) Term: **15 Years**

(21) Appl. No.: **29/887,574**

(22) Filed: **Mar. 22, 2023**

(30) **Foreign Application Priority Data**

Dec. 16, 2022 (CN) 202230842897.8

(51) **LOC (15) Cl.** **26-04**

(52) **U.S. Cl.**

USPC **D26/1**

(58) **Field of Classification Search**

USPC D26/139, 38, 39, 1, 2, 3, 4, 24, 25, 27, D26/37, 42, 93, 105, 120, 28, 34

CPC F21S 8/02; F21S 8/33; F21S 8/04; F21S 8/085; F21S 8/026; F21V 5/007; F21V 5/008; F21V 5/00

(57) **CLAIM**

The ornamental design for a LED package as shown and described.

DESCRIPTION

FIG. 1 is a front view of a LED package showing our new design according to a first embodiment;
FIG. 2 is a left side view shown in FIG. 1;
FIG. 3 is a right side view shown in FIG. 1;
FIG. 4 is a top plan view shown in FIG. 1;
FIG. 5 is a bottom plan view shown in FIG. 1;
FIG. 6 is a rear view shown in FIG. 1;
FIG. 7 is a perspective view shown in FIG. 1.
FIG. 8 a front view of a LED package showing our new design according to a second embodiment;
FIG. 9 is a left side view shown in FIG. 8;
FIG. 10 is a right side view shown in FIG. 8;
FIG. 11 is a top plan view shown in FIG. 8;
FIG. 12 is a bottom plan view shown in FIG. 8;
FIG. 13 is a rear view shown in FIG. 8; and,
FIG. 14 is a perspective view shown in FIG. 8.
